DISPENSING MACHINE ESCAPEMENT
MECHANISM

Charles C. Kuhl, South Bend, Ind.

Application August 3, 1939, Serial No. 288,109

14 Claims. (Cl. 74—162)

This invention relates to dispensing machine escapement mechanism, and more particularly to means for operating a rotatable member of a dispensing machine as illustrated in my copending application, Serial No. 288,101, filed August 3, 1939, step-by-step in a series of partial rotating movements.

The primary object of the invention is to provide means for rotating a rotatable member to a predetermined extent in one direction only upon each operation.

A further object is to provide a device of this character having a rotatable member with means for preventing spinning of said member.

15 A further object is to provide a device of this character having a rotatable member, with means for rotating said member which engage said member at its periphery for driving connection therewith.

20 Other objects will be apparent from the description and the appended claims.

In the drawings:

Fig. 1 is a fragmentary side view of the device with the casing shown in section.

25 Fig. 2 is an enlarged fragmentary sectional view of the device taken on line 2—2 of Fig. 3, and viewed from the lower end of the dispenser reel.

30 Fig. 3 is an enlarged fragmentary top plan view of the device in normal position.

Fig. 4 is an enlarged fragmentary top plan view of the device in partial operating position.

Referring to the drawings, which illustrates the preferred embodiment of the invention, the numeral 10 designates an insulated casing or housing for the dispenser, and 11 a storage or cooling chamber in the lower end of said casing. A frame is mounted in the case and includes uprights 12 and suitable horizontal cross bars 13 between said uprights.

40 A shaft 14 is carried by suitable mounting members 15 supported on cross bars 13, said shaft being inclined. Upon the shaft 14 is journaled a reel 16 adapted to carry a plurality of bottles 17. Reel 16 preferably comprises an elongated hub 18 journaled in shaft 14 and carrying a plurality of equi-spaced partition plates 19 radially projecting therefrom, said plates extending parallel to shaft 14. The outer ends of plates 19 are connected together by and carry an outer peripheral member 20 preferably of polygonal outline or shape. Plates 19 and peripheral member 20 provide a plurality of radially inwardly tapered, elongated compartments into which bottles 17 freely fit. Longitudinal guides 21 may be

secured adjacent the large dimension outer end of the compartments to project therein for guiding and positioning the bottles. Suitable bottle discharge means (not shown) are provided at the lower end of the reel, and an inclined discharge trough 22 may extend from said discharge means to and through casing 10. The outer peripheral member 20 carries a plurality of elongated, circumferentially arranged projecting members 23. Members 23 are equal in number to the number 10 of bottle compartments, and each is centered relative to one of said compartments. Each of the members 23 is set at a slight angle relative to true circumferential position whereby the adjacent ends of adjacent members are slightly offset from each other as illustrated in Figs. 3 and 4. The members 23 are also slightly circumferentially spaced opposite the outer ends of partitions 19. For purposes of clarity, and referring solely to Figs. 2, 3 and 4, those members 23 which are juxtaposed to the escapement mechanism to be hereinafter described will be referred to as 23a, 23b, 23c, and 23d.

45 A pair of spaced parallel guide bars 24 are carried by the frame 12, 13 adjacent the upper end thereof and extend transversely of shaft 14. One member 24 is positioned slightly above the other, with the angle of inclination of the plane between said members parallel to the axis of shaft 14. The intermediate portions 25 of members 24 are curved concentric of shaft 14 and are positioned in slightly spaced relation above real projections 23. Portions 25 of guide members 24 are each provided with guide means, such as slots 26, at their inner faces.

50 A block or shoe 27 of a width substantially equal to the spacing between guides 24 is positioned between portions 25 of said guides, and has suitable guides thereon (not shown) slidably engaging in slots 26 whereby said shoe 27 is slidable between guides 24 to an extent limited by the ends of slots 26.

55 A bellcrank lever 28 is pivoted intermediate its ends at 29 at one end of shoe 27. Lever 28 carries an upwardly projecting stud 30 at one end thereof and to this stud 30 is connected a bracket 31 to which one end of a suitable operating cable 32 is connected. An elongated coil spring 33 is connected at one end to stud 30 and extends in opposed relation to cable 32 with its outer end connected to the frame. A stop 34 carried by the shoe 27 serves to limit the pivotal movement of member 28 by spring 33 to the position illustrated in full lines in Fig. 3; so that 55

spring 33 may also act to normally position the shoe 27 as illustrated in Figs. 2 and 3.

At the end of shoe 27 opposite lever 23 a dog 35 is pivoted at 36, said dog extending beyond the 5 end of shoe 27 and terminating in a downwardly extending lug 37. A spring 38 secured at its ends to dog 35 and shoe 27 serves to normally position said dog longitudinally of the shoe and in alignment with the rear end of adjacent reel projection 10 23a. A dog 39 is pivoted to the shoe 27 at 40 in laterally spaced relation to dog 35. Dog 39 projects beyond the end of shoe 27 and is provided with a downwardly bent lug 41 at its free outer end. Lug 41 is perpendicular to dog 39, but is 15 twisted whereby its lower end extends at an angle to the longitudinal with respect to said dog. The leading edge of lug 41 engages the side of the reel projection 23a slightly in advance of lug 37, while the trailing edge portion of lug 41 extends across 20 the front edge of the succeeding reel projection 23b for purposes to be set forth. Dog 39 carries an upwardly projecting lug 42 intermediate its ends at its outer side. A spring 43 is connected 25 at its ends to stop 34 and dog 39 to normally urge said dog in the direction of dog 35 and against reel projection 23a with respect to which its pivot 40 is laterally off-set.

In spaced relation to the end of shoe 27 which mounts member 28, a locking bar 44 is slidably 30 mounted by guides 25 transversely thereof. A lug 45 projects downwardly from one longitudinal edge of bar 44 intermediate guides 25. A transverse upwardly extending lug 46 is also carried by bar 44 adjacent the free end of member 28. A 35 spring 47 extending between lug 46 and adjacent guide 25 serves to normally position the bar 44 in full line position of Fig. 3, to position lug 45 in engagement with the leading edge of reel projection 23c.

40 A second locking bar 48 is spaced from bar 44 in counter rotational direction, and is slidably between guides 25 transversely thereof. Bar 48 carries a lug 49 projecting perpendicularly downwardly therefrom and twisted or bent to position 45 its lower end at an angle to the longitudinal dimension of bar 48. A spring 50 connected at its ends to guide 25 and bar 48 serves to urge bar 48 in opposite direction to the action of spring 47 with respect to bar 44. In normal spring pressed 50 position of bar 48, the lug 49 extends adjacent to and in alignment with the rear edge of reel projection 23c and is urged into engagement with the side of the leading end portion of the next succeeding reel projection 23d.

55 Forwardly spaced from the normal inoperative position of lug 42 of dog 39 a distance equal to or slightly greater than the length of a reel projection 23 is a stop member 51 carried by guide 25 adjacent dog 39. Stop 51 has an inwardly extending cam projection 52 adapted to be engaged by lug 42 of dog 39 for purposes to be set forth.

The operation of the device is as follows: In 60 normal inoperative position of the parts, lug 41 of dog 39 and lug 45 of locking bar 44 engage or extend transversely across the leading edges of reel projections 23b and 23c respectively, and serve to hold the reel against rotation in one 65 direction. Lug 37 of dog 35 and lug 49 of locking bar 48 engage or extend transversely across the trailing edges of reel projections 23a and 23c, respectively, and serve to hold the reel against rotation in the opposite direction. Hence the reel 70 is held solidly against any movement to discharge 75

ing position, regardless of shaking or rough handling of the device.

To actuate the device, the cable 32 must be pulled, as by suitable means exteriorly of casing 10 which is preferably coin controlled. Initial pull 5 on cable 32 serves to pivot the lever 23 to dotted line position in Fig. 3 whereby the free end of said lever engages lug 46 of locking bar 44 to shift it against the action of spring 47 to the dotted line position illustrated wherein lug 45 10 thereof is laterally shifted with respect to the leading edge of reel projection 23c. Thereafter, continued pull on cable 32 serves to slide the shoe 27 on guides 25, and thereby rotate the reel by virtue of engagement of lug 37 of dog 35 with the 15 trailing edge of reel projection 23a. Before movement of the shoe 27 sufficient to disengage lug 46 of locking bar 44, the reel projection 23c will have been shifted with its leading edge beyond lug 45 so that lug 45 bears against the side of said 20 projection and locking bar 44 is rendered inoperative. The lug 41 of dog 39, being moved by shoe 27, does not interfere with reel rotation by means of said shoe. Thus, when the cable has been moved substantially one-half of its operative 25 movement, the parts will assume the positions illustrated in Fig. 4, with lugs 37 and 41 remaining in their normal relation to reel projections 23a and 23b, lug 45 bearing against an intermediate portion of reel projection 23c at one side thereof 30 and lug 49 bearing against an intermediate portion of reel projection 23d at the side thereof opposite lug 45. Each of lugs 45 and 49 are spring pressed against their respective reel projections.

When cable 32 has been operated for substantially the full extent of its operating movement, lug 42 of dog 39 engages cam 52 of stop 51, so that concluding movement of shoe 27 serves to pivot lug 41 of dog 39 laterally outwardly clear of the leading end of reel projection 23b. At 40 the same time dog 39 is being so pivoted, the trailing end of reel projection 23d will have passed lug 49, thereby permitting locking bar 48 to assume its normal position behind the trailing edge of projection 23d urged by spring 50. 45 The shoe 27 is moved only slightly beyond the point at which lug 48 engages cam 52. After the cable has completed its movement and is released, spring 33 urges shoe 27 and its associated parts to normal position. During this 50 return movement of the shoe the lugs 37 and 41 ride on opposite sides of projection 23b.

The reel cannot be spun or freely rotated regardless of the speed or manner with which cable 32 is pulled or jerked, by reason of the 55 position of the various lugs 37, 41, 45 and 49 with respect to the reel projections 23, nor can said reel be rotated through an angle greater than that between adjacent reel partitions 19 on any one cable operation. The lug 45, bearing on 60 the side of projection 23c after initial movement of shoe 27, is positively positioned in advance of projection 23d to prevent forward spinning, and lug 49 bearing against the side of lug 23d is positioned behind the projection 23c to prevent reverse spinning. Also, the arrangement of the parts is such that if the cable is only partially operated and then released, as with intent to obtain a new purchase for the purpose of actuating the reel more than normal operative extent, the reel will strictly follow the movement of shoe 27, and will be reversely rotated to starting position by reason of the location of lug 41 70 forwardly of reel projection 23b. It will thus be observed that the escapement mechanism 75

guards against any type of manipulation for the purpose of pilfering the reel, assuming, of course that suitable coin control means are associated with the cable operating mechanism to prevent unauthorized repetitive complete operations of said cable.

In order to permit filling of the reel which may require free rotation thereof, the dog 39 and locking bar 44 may be shifted to inoperative positions by suitable means (not shown) positioned interiorly of the casing 10 to be accessible only by an authorized attendant.

I claim:

1. The combination with a rotatable member having a plurality of circumferentially arranged peripheral projections positioned at an angle to the direction of rotation of said member, of a guide positioned adjacent the periphery of said member, a carrier slidable on said guide, means for actuating said carrier a predetermined extent, a spring pressed member pivoted to said carrier and normally engaging the trailing edge of one projection, and means for returning said carrier to normal position whereby said pivoted member rides along the succeeding projection to a position therebehind.

2. The construction defined in claim 1, and means for stopping said rotatable member upon predetermined movement of said carrier.

3. The construction defined in claim 1, and a second spring pressed member pivoted to said carrier and normally extending in front of one of said projections.

4. The construction defined in claim 1, including a second spring pressed member pivoted to said carrier and normally extending in front of one of said projections, and means on said guide engaged by said second member for stopping said carrier and shifting said second member laterally of said last named projection.

5. The combination with a rotatable member having a plurality of circumferentially arranged peripheral projections each positioned at an angle to the direction of rotation of said member, of a guide positioned adjacent the periphery of said member, a carrier slidable on said guide between predetermined limits, means for actuating said carrier, a spring pressed propeller pivoted to said carrier and normally engaging the rear end of one projection in laterally spaced relation to the succeeding projection, a spring pressed retarder pivoted to said carrier and normally positioned in front of the front edge of a projection, and means for laterally swinging said retarder clear of said last named projection at one limit of travel of said carrier, and means for returning said carrier to its opposite limit of travel.

6. The construction defined in claim 5, and means carried by said guide and extending transversely of and adjacent the forward end of a projection upon engagement of said retarder with said swinging means.

7. The combination with a rotatable member having a plurality of circumferentially arranged peripheral projections positioned at an angle to the direction of rotation of said member, of a guide positioned adjacent the periphery of said member, a carrier slidable on said guide, a spring pressed member pivoted on said carrier, propelling means connected with said pivoted member in opposition to said spring, locking means shiftably carried by said guide adjacent said pivoted member and normally positioned in front of one

of said projections, said pivotal member laterally shifting said locking means upon initial actuation of said propelling means and thereafter shifting said carrier, and means on said carrier engaging one of said projections to shift said member therewith.

8. The construction defined in claim 7, wherein said locking means is spring pressed for return to locking relation with respect to the succeeding projection upon shifting of said carrier for disengagement of said pivoted member with said locking means.

9. The construction defined in claim 7, and a second locking member shiftably carried by said guide positioned behind a projection and spring pressed against the side of the front portion of the succeeding projection.

10. The combination with a rotatable member having a plurality of circumferentially arranged spaced projections, a stationary guide member having a curved portion substantially concentric with the periphery of said rotatable member, actuating means shiftable on said curved guide portion and engaging a projection for rotating said member, stop means carried by said stationary member and engageable with a projection for limiting rotation of said member by said actuating means and means carried by said actuating means for disengaging said stop means upon initial operation of said actuating means.

11. The construction defined in claim 10, and means carried by the curved portion of said guide member and engageable with a projection for restraining said member from reverse rotation upon return of said actuating means.

12. The combination defined in claim 10, and means carried by said actuating means and normally positioned in advance of one of said projections to limit speed of rotation of said member to conform to the speed of said actuating means.

13. The combination with a rotatable member having a plurality of circumferentially arranged spaced projections each extending at an angle to the direction of rotation of said member, a stationary guide member juxtaposed to the periphery of said rotatable member, a carrier slidable on said guide, a bell-crank pivoted to said carrier, an actuating member connected to one end of said bellcrank, a spring connected to said bellcrank in opposition to said actuating member, a spring pressed locking member slidably transversely of said carrier by said bellcrank and having a part normally positioned in alignment with the front end of a projection, a second locking member slidable transversely of said carrier positioned in alignment with the rear end of a projection and spring pressed against the side of an adjacent projection, and means on said carrier and engaging adjacent ends of adjacent projections for shifting said rotatable member with said carrier, said actuating member shifting said carrier after initially pivoting said bellcrank.

14. The construction defined in claim 13, wherein said last named means includes a shiftable member normally positioned in alignment with the front end of a projection; and means on said guide spaced from the normal position of said shiftable member a distance substantially equal to the length of a projection and adapted to be engaged by said shiftable member to laterally shift the same.

CHARLES C. KUHL,
